(57) **CLAIM**

The ornamental design for a wheel with 5 curved split spokes, as shown and described.

DESCRIPTION

FIG. 1 is a perspective view of the front or outer side of my wheel with 5 curved split spokes taken from slightly above and to one side. The reverse or inner side of the wheel is identical to the front side; and,

FIG. 2 is an cross-sectional view of the wheel of FIG. 1 taken along the lines 2—2 of FIG. 1.
